TRIMMING.

No. 17,649.

Patented Aug. 23, 1887.

i Fig. 1.

Fig. 2.

UNITED STATES PATENT OFFICE.

BENJAMIN LIPPER, OF PHILADELPHIA, PENNSYLVANIA.

DESIGN FOR TRIMMING.

SPECIFICATION forming part of Design No. 17,649, dated August 23, 1887.

Application filed June 27, 1887. Serial No. 242,695. Term of patent 3½ years.

To all whom it may concern:

Be it known that I, BENJAMIN LIPPER, a citizen of the United States, and a resident of Philadelphia, Pennsylvania, have invented a new and Original Design for Trimming, of which the following is a specification.

My design for a trimming is fully illustrated in the accompanying photographs, which show two forms of trimming, both of which embody

10 the essential features of the design.

The design comprises bands *a a*, with intervening band, *f*, and outlying bands *g*. The bands *a a* are ornamented with rows *b* of loops of close texture or braid-like character, adjacent 15 to which are rows *d* of loosely-grouped open bunches of loops, and the ornamentation of the bands *a* is raised above the surface of the bands *f* and *g*, so that the said bands serve to border or bring into relief the bands *a a*.

20 As shown in Fig. 1, each band *a* consists of but one row *b* and one row *d*, while in Fig. 2 each band *a* consists of two rows *b* and an interposed row *d*, the general effect in the two

cases, however, being substantially the same.

I claim—

1. The within-described design for a trimming, said design consisting of raised bands *a* and intervening band, *f*, the bands *a* being composed of rows *b* of loops of braid-like character and rows *d* of loosely-grouped open 30 bunches of loops, all substantially as described and shown. 25

2. The within-described design for a trimming, said design consisting of raised bands *a*, intervening band, *f*, and outlying bands, *g*, 35 said bands *a* being composed of rows *b* of loops of braid-like character and rows *d* of loosely-grouped open bunches of loops, all substantially as described and shown.

In testimony whereof I have signed my name 40 to this specification in the presence of two subscribing witnesses.

BENJAMIN LIPPER.

Witnesses:

WILLIAM D. CONNER,
HARRY SMITH.
